PICKET FENCE

Allen Fischer and Karl A. Bauridl, Jr.,
St. Louis County, Mo.

Application November 29, 1954, Serial No. 471,827

8 Claims. (Cl. 256—22)

This invention pertains to a picket fence which may be constructed of metal, such as aluminum or the like.

An object of this invention is to provide a fence structure which may be prefabricated in separate fence elements and which can be assembled in a simple manner without the use of special tools.

Another object is to provide such a fence structure by which unskilled workmen may assemble the fence easily and produce a neat and workmanlike job.

Further objects will appear from the following description taken in connection with the accompanying drawings, in which—

Fig. 1 is a front view, partly broken away, of a fence constructed in accordance with this invention;

Fig. 2 is a section on line 2—2 of Fig. 1, enlarged;

Fig. 3 is a section of one of the pickets on line 3—3 of Fig. 1, enlarged;

Fig. 4 is an enlarged front view of a shoe for connecting the picket to the fence rail; and

Fig. 5 is a right-hand end view of Fig. 4.

Referring to the drawings, a fence constructed in accordance with this invention comprises one or more, usually two, horizontal fence rails 1 supported on suitable upright posts 2. A series of pickets 3 is attached at regular intervals to the rail or rails 1 in upright position, as shown in Fig. 1.

Each of the pickets 3 is constructed of a wide strip of metal formed to the shape shown in cross-section in Fig. 3. In this form, the middle portion of the strip is formed to provide a rectangular bead 4 having side flanges 5 extending rearward from the front face of the picket. This structure forms the bead 4 as seen from the rear of the picket, or a channel as seen from the front. On both sides of this channel, side wing portions 6 extend outward from the front edges of the flanges 5. These wing portions are positioned at an angle to a horizontal plane, as seen in Fig. 3, or to the plane of the fence when the picket is mounted in its place in the fence. The side edge portions of the strip are bent to the rear to form rounded side edges 7 on the picket and rear flange portions 8. The inner edges of these flange portions 8 are substantially in the same plane with or slightly in rear of the rear face of the bead 4 so as to make spring contact with the rail 1. The picket is formed to the cross-sectional shape shown in Fig. 3 throughout its length, excepting at the top, which may be finished off to any desired contour such as a curve 9, Fig. 1. This upper portion may also be flattened, as shown at 10, Fig. 2.

The horizontal fence rails 1 may be formed to a general box shape in cross-section, as shown in Fig. 2, with the front edges turned in to form upper and lower flanges 11, the rest of the front face being open. These rails may be attached to the posts 2 in any suitable manner, as by means of U-bolts 12. These posts may be any desired cross-sectional shape, an ordinary square section being usual.

In order to attach the picket 3 to the rail 1, a shoe 20

2

is provided, as shown in Figs. 4 and 5. This is a rectangular strip of metal arranged with its long dimension horizontal and having its upper and lower edge portions bent rearward to form flanges 13. These flanges are dimensioned to fit within the rail 1 and up against the inner faces of the flanges 11 thereof. Just within the flanges 13, the edge portions of the shoe are formed with a slight offset 14 toward the rear. The distance of this offset portion from the front face of the shoe is slightly less than the thickness of the metal of which the rail 1 is made. For example, if the thickness of the metal is .040 of an inch, the offset would be about .030 of an inch. The purpose of this will be explained presently. The shoe 20 is longer than the width of the picket as shown in Fig. 1.

A rivet hole 15 is formed in the shoe at about its center, as shown in Fig. 4. On each side of the rivet hole 15, a bead 16 is struck inward or toward the rear of the shoe, as shown in Figs. 4 and 5. These beads extend transversely of the shoe or vertically in the finished fence. Their spacing from each other is such that when the shoe is attached to the picket, they will be substantially aligned with the flanges 5 of the bead 4. A similar rivet hole is formed in the picket on the center line of the bead 4 and the shoe is attached to the picket by means of a rivet 17 engaging these holes when aligned and securing the shoe rigidly to the picket in a position extending transversely thereof, as shown in Fig. 1.

When the fence is erected, the rails 1 are mounted on the posts 2. The pickets are then assembled to the rail 1 by inserting the shoe into the rail 1 with the offset portions 14 of the shoe behind the flanges 11 of the rail. The picket is then slid along the rail until the end of the shoe contacts the end of the shoe on the preceding picket. Thus the length of the shoe fixes the spacing of the pickets as the pickets are moved along the rails until their shoes are all in contact. Since the offset of the portion 14 of the shoe is less than the thickness of the flange 11, the rear flange portion 8 of the picket which contacts the outer face of the flange 11 opposite the portion 14 of the shoe will bear against the front face of the flange 11 with a spring pressure produced by the resilient yielding of the wing portions 6 of the picket. Thus, each picket will be securely held in place on the rail 1 by the friction produced by this spring pressure.

It will be seen that this invention provides a structure very easily assembled on the job. The rails may be mounted on the posts 2 first, and then the pickets assembled, or a proper number of pickets may be assembled on a pair of rails to form a finished section and then successive sections may be put in place by mounting the rails 1 on the posts 2.

Since the shoes may swivel on the rivets 17, the rails may be set at an angle to the pickets, as when the fence is on a slope.

Various changes may be made in the details of construction, within the scope of the appended claims, without departing from the spirit of this invention. Parts of the invention may be used without the whole and improvements may be added while retaining some or all of the advantages of the invention.

We claim:

1. A picket fence, comprising a strip of sheet metal formed to provide a picket having a central bead extending therealong and inturned side edge portions, a horizontally extending shoe secured to said picket at said bead with its upper and lower edge portions engaging the side edge portions of said picket, and a supporting rail having in-turned flanges, said picket being attachable to said rail by inserting said flanges between said edge portions of said picket and said shoe whereby said flanges are gripped by spring pressure of said edge portions.

2. A picket fence, comprising, a sheet metal picket, a shoe longer than the width of said picket attached thereto to extend transversely thereof, and a supporting rail having means engageable by said shoes of a plurality of pickets to support the picket, said shoes being in end-to-end engagement, their length fixing the spacing of the pickets.

3. A picket for a picket fence, comprising, a strip of sheet metal formed with a longitudinal channel along its middle providing a bead projecting rearward therefrom, and flat side flanges along said strip having their edges bent rearward into U-form providing rounded side edges for the picket and rear flange portions positioned for spring contact with a rail engaging said bead.

4. A picket for a picket fence, comprising, a strip of sheet metal formed with a longitudinal channel along its middle providing a bead projecting rearward therefrom, and side flanges along said strip bent rearward into U-form providing rounded side edges for the picket, and extending rearward to alignment with the same face of 20 said bead to make spring contact with a rigid supporting fence rail also engaged by said bead.

5. A fence picket, comprising, a strip of sheet metal formed with a rectangular middle channel therealong, flat side wing portions extending laterally from said channel and angularly to the plane of the fence, and side edge portions bent rearward and inward providing rounded edges for the picket and spring-contact members for engaging the same face of a supporting rail also engaged by the web portion of said channel.

15

20

30

6. In combination with a fence-picket formed with a bead projecting rearward therefrom, a mounting shoe, and means for clamping said shoe to said picket, said shoe being formed with a stiffening bead in alignment with the bead on said picket when said shoe is clamped by said clamping means.

7. A picket fence, comprising, horizontal rails of box form having in-turned upper and lower front flanges, a series of pickets each formed of a strip of sheet metal formed to provide a middle bead therealong and angularly extending side wing portions, shoes secured to each of said pickets to extend transversely thereof, said pickets being mountable on said rails by engaging said shoes within the rails with said in-turned flanges spring-clamped between said shoes and said wing portions of said pickets.

8. A picket fence in accordance with claim 7 in which the shoes are longer than the width of the pickets and when in contact with each other determine the spacing of the picket along the fence.
